MULTIPLE-SPEED PHONOGRAPH
TURNTABLE

Richard W. Sears, II, Grayslake, Ill.

Application December 13, 1941, Serial No. 422,827

9 Claims. (Cl. 274—9)

This invention relates to sound reproducing apparatus and more particularly to a turn-table for phonographs or the like.

In the reproduction of sound from flat or disc-shaped records it is necessary that the record be rotated at a speed corresponding to the speed of recordation. It has, accordingly, been the practice to record the sound at a standard speed of rotation of the record and to provide a turn-table on reproducing machines such as a phonograph which is driven at a similar speed of rotation. While a large part of the records now on the market are recorded at this standard speed, there are also certain records available which are recorded at a much slower speed to record a correspondingly greater number of sounds for each rotation of the record.

It is, accordingly, a primary object of the present invention to provide a simple, relatively inexpensive and readily attached turn-table device for a phonograph or the like which is adapted for the reproduction of sound from records recorded at different speeds of rotation.

A further object is the provision of a multi-speed turn-table adapted to be readily and simply applied to a sound reproducing machine, such as a phonograph, having a standard speed of rotation.

A further object is the provision of a multi-speed turn-table adapted for ready attachment to an existing turn-table having a predetermined speed of operation.

Another object is the provision of a turn-table directly mountable upon an existing turn-table of standard speed and selectively operable at either the speed of the existing turn-table or at a different speed.

A still further object is the provision of simple and effective means for changing the speed of a multi-speed turn-table.

Still another object is the provision of speed changing mechanism for turn-tables which is disposed substantially entirely below the turn-table.

These and other objects will be apparent from the following description, the appended claims, and the attached drawing in which:

Fig. 1 is a plan view, partly broken away, showing an embodiment of a turn-table constructed in accordance with the present invention;

Fig. 2 is a vertical section taken on the line 2—2 of Fig. 1; and

Fig. 3 is a fragmentary view of a part of the mechanism shown in Fig. 1 and illustrating the parts in a second operative position.

Referring to the drawing which illustrates a selected embodiment of the invention, reference numeral 10 designates the housing of a phonograph or like sound reproducing apparatus having a shaft 11 extending upwardly therefrom. A

turn-table 12 provided with a record centering plug or projection 13 is mounted on the shaft 11 for rotation therewith. The table 12 is the usual record supporting turn-table provided with a phonograph apparatus, and is adapted to be rotated at a constant speed by a drive mechanism (not shown) located within the housing 10. This speed, for example, may be approximately 78 R. P. M. The parts thus described are standard equipment on present phonograph apparatus.

In accordance with the present invention, a turn-table device is provided which is adapted for operation at different speeds, and in the illustrated embodiment the construction is such that the device can be directly seated upon the turn-table of an existing machine, such as the turn-table 12 above described. To this end a turn-table 14 is provided and is rotatably mounted on a base member 15. The base member 15 is adapted to be rotated at the same speed as the shaft 11, and, as illustrated, comprises a relatively flat portion 16 of substantial area which merely sits on the top of the turn-table 12 with the projection 13 of the turn-table providing a center for the base member. The portion 16 of the base member thus frictionally engages the upper surface of the turn-table 12 and is rotated at the same speed as the turn-table 12 upon rotation of the shaft 11.

An upstanding hub member 17 is provided on the base 15 and supports a hub or sleeve member 18, which is fixed thereto by a pin 19 and is provided with a hollow interior adapted to be removably received over the centering plug 13. A plug 20 is rotatably received within a seat 21 provided in the upper portion of the member 18 and provides for rotatably supporting the turn-table 14 on the member 18. The plug 20 is also provided with an upwardly extending projection 22 which serves as a centering member to locate the center of a record with respect to the turn-table 14.

The member 18 also provides a journal for an arm 25 provided with a bearing portion 26, which is rotatably mounted on the member 18 above the hub member 17. The member 18 above the bearing 26 extends laterally outwardly, as indicated at 27, to provide a gear having teeth 28. A gear 29 is rotatably mounted upon the arm 25, as indicated at 30, and has meshing engagement with the teeth 28 of the gear 27 provided on the member 18. The gear 29 also has meshing engagement with an internal ring gear 31 fixedly attached to the turn-table 14, as by rivets 32 and provided with internal teeth 33 which mesh with the teeth of the gear 29.

The arm 25 extends outwardly beyond the ring gear 31 and is provided with a laterally extending arm 35 at its outer end. A multi-fingered member indicated generally by the numeral 36 is

pivotedly mounted upon the outer end of the arm 25 as indicated at 37. The member 36 comprises angularly related finger portions 38 and 39 and an arm 40 provided with an upwardly extending brake shoe 41 adapted to engage the outer periphery of the ring gear 31.

A spring 45 is tensioned between a pin 46 provided on the portion 35 of the arm member 25 and a pin 47 provided on the finger portion 39 of the member 36. The pins 46 and 47 are so located with respect to the pivot axis 37 of the member 36 that the spring 45 tends to urge the brake shoe 41 into engagement with the outer periphery of the ring gear 31 when the parts are in the location shown in Fig. 1.

The member 36 is adapted, however, to be rotated about its pivot 37 in a clockwise direction, as viewed in Fig. 1, to move the brake 41 away from the ring gear 31. This movement of the member 36 is effected by engaging the finger portion 38 of the member 36 with a finger of an operator and manually moving the finger 38 downwardly. A stop member 48 provided on the finger portion 39 and engageable with the arm 25 provides for limiting this movement of the member 36.

Upon movement of the finger member 38 clockwise and downwardly, as viewed in Fig. 1, to move the brake shoe 41 away from the ring gear 31, the spring 45 is so arranged as to snap over the pivot 37 and maintain the stop member 48 into engagement with the arm 25. In this position the brake member 41 is entirely disengaged from the periphery of the ring gear 31, and the member 36 assumes the angular position shown in Fig. 3 with respect to the arm 25.

When the brake 41 is in engagement with the ring gear 31, as shown in Fig. 1, the gears 27, 29 and 31, together with the arm 25, are locked against relative rotation and the entire mechanism including the turn-table 14 is rotated as a unit about the axis of the turn-table in accordance with rotation of the shaft 11 and the turn-table 12. This rotation is such as to move the turn-table in a clockwise direction, as indicated by the arrow in Fig. 1.

Upon manual movement of the member 36 to the position shown in Fig. 3, however, a stop pin 50 provided on the finger member 39 is moved into a position to be engaged by a fixed stop 51 carried by an arm 52 rigidly attached to the housing 10 as indicated at 53. The stop 51 in cooperation with the stop pin 50 therefore prevents rotation of the member 36 and the arm 25 about the axis of the turn-table when the shaft 11, turn-table 12 and base member 15 are rotated.

With the arm 25 thus locked against rotation and the brake means 41 released, the turn-table is rotated through the intermediary of the gears 27, 29 and 31. The turn-table 14 thus rotates at a reduced speed with respect to the rotation of the turn-table 12 depending upon the gearing ratio of the gears 27, 29 and 31. Thus the turn-table 15 may be rotated at a speed of approximately 34.2 R. P. M., which is a desired speed for rotating certain records having more than the usual sound recordings arranged along each circumferential groove of the record.

The mechanism just described drives the teeth 28 on extension 27 in a clockwise direction with the rotation of the turn-table 12. This in turn drives the gear 29 in a counter-clockwise direction, and since gear 29 mates with the internal teeth 33 on gear 31, it, too, will be driven in a

counter-clockwise direction. The rotation of gear 31 in a counter-clockwise direction is transmitted directly to the turn-table 14 and, accordingly, it also is driven in a counter-clockwise direction. Reversal of the direction of rotation of the turn-table 14, it will readily be understood, may be accomplished in any conventional manner as by a reversal of the parts.

When it is desired to again rotate the turn-table 15 at the same speed as the shaft 11 and turn-table 12, it is merely necessary to engage the finger piece 38 by an operator's finger and manually move the member 36 from its position in Fig. 3 to its position in Fig. 1. This causes the brake member 41 to again engage the ring gear 31 under action of the spring 45 and moves the stop pin 50 out of engagement with the fixed stop 51. All of the parts, including the arm 25, are thus again free to rotate as a unit about the axis of the turn-table.

A multi-speed turn-table for phonographs and the like is thus provided, which may be very simply and readily applied to existing phonograph apparatus. A simple and effective mechanism for rotating a turn-table at various speeds is provided. The speed changing mechanism is located substantially entirely beneath the turn-table. The entire device can be applied by merely placing it on the top of a constant speed turn-table.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A turn-table for phonographs or the like comprising a member adapted to be rotated at a predetermined speed, a turn-table rotatively mounted on said member, an arm rotatively mounted on said member, a gear fixed to said member for rotation therewith, an internal ring gear attached to said turn-table and lying in substantially the same plane as said gear, and an idler gear carried by said arm in the plane of the first named gear and the ring gear for interconnecting said first named gear with said ring gear.

2. A turn-table for phonographs or the like comprising a member adapted to be rotated at a predetermined speed, a turn-table rotatively mounted on said member, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, and brake means carried by said arm and movable into engagement with said ring gear for locking said ring gear and said arm together for rotation with said member.

3. A turn-table for phonographs or the like comprising a member adapted to be rotated at a predetermined speed, a turn-table rotatively mounted on said member, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, brake means carried by said arm and

movable into engagement with said ring gear for locking said ring gear and said arm together for rotation with said first named member, manually operable means for releasing said brake means, and means for maintaining said arm against rotation upon release of the brake means to effect rotation of said turn-table through said gearing.

4. A turn-table for phonographs or the like comprising a member adapted to be rotated at a predetermined speed, a turn-table rotatively mounted on said member for rotation about an axis, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, a member pivotally mounted on said arm for movement about an axis substantially parallel with said axis of the turn-table, brake means carried by said pivotally mounted member for locking said ring gear and said arm together for rotation with said first named member, means on said pivotally mounted member and extending laterally thereof for manually moving the member about its pivot to release said brake means, and stop means for maintaining said arm against rotation upon release of said brake means.

5. A turn-table for phonographs or the like comprising a member adapted to be rotated at a predetermined speed, a turn-table rotatively mounted on said member for rotation about an axis, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, a multi-armed member pivotally mounted on said arm for movement about an axis substantially parallel with said axis of the turn-table, brake means carried by said multi-armed member for locking said ring gear and said arm together for rotation with said first named member, one of the arms of said multi-armed member extending laterally of the member and providing for manually moving the member about its pivot to release said brake means, a second arm of the last named member being provided with a stop member, a fixed stop cooperating with said stop member for maintaining said first named arm against rotation upon release of said brake means, and means including an off-center spring connected between said first named arm and one of said latter named arms for maintaining said multi-armed member in either a brake engaging position or a stop engaging position.

7. A turn-table for phonographs or the like comprising a member adapted to be rotated at a predetermined speed, a turn-table rotatively mounted on said member for rotation about an axis, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, a multi-armed member pivotally mounted on said arm for movement about an axis substantially parallel with said axis of the turn-table, brake means carried by said multi-armed member for locking said ring gear and said arm together for rotation with said first named member, one of the arms of said multi-armed member extending laterally of the member and providing for manually moving the member about its pivot to release said brake means, a second arm of the last named member being provided with a stop member, a fixed stop cooperating with said stop member for maintaining said first named arm against rotation upon release of said brake means, and means including an off-center spring connected between said first named arm and one of said latter named arms for maintaining said multi-armed member in either a brake engaging position or a stop engaging position.

8. A turn-table for phonographs or the like comprising a member adapted to be rotated at a predetermined speed, a turn-table rotatively mounted on said member, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, cooperating stop means between said arm and a fixed support for maintaining said arm against rotation, and manually operable means for selectively engaging or releasing said cooperating stop means.

9. A turn-table for phonographs or the like comprising a housing, a member mounted on the housing and adapted to be rotated at a predetermined speed, a turn-table rotatively mounted on said member, an arm rotatively mounted on said member, a gear fixed to said member for rotation therewith, an internal ring gear attached to said turn-table and lying in substantially the same plane as said gear, an idler gear carried by said arm in the plane of the first named gear and the ring gear for interconnecting said first named gear with said ring gear, brake means for locking said ring gear and said arm together for rotation with said member, a fixed support on the housing, cooperating stop means between said arm and the fixed support for maintaining said arm against rotation upon release of said brake means, and manually operable means for selectively engaging or releasing said brake means and said cooperating stop means.

RICHARD W. SEARS, II.
